UNITED STATES PATENT OFFICE

ADOLPH F. HOTTINGER, OF CHICAGO, ILLINOIS, ASSIGNOR TO NORTHWESTERN TERRA COTTA COMPANY, OF CHICAGO, ILLINOIS, A CORPORATION OF ILLINOIS

TERRA-COTTA ARTICLE

Original application filed October 3, 1927, Serial No. 223,542. Divided and this application filed November 10, 1928. Serial No. 318,362.

The present invention relates to terra cotta articles.

The present invention is a division of the application filed by the present applicant on October 3, 1927, Serial No. 223,542, entitled Methods for making terra cotta articles.

In the making of terra cotta articles it has been common practice to provide a mold and lining the face and sides of said mold with layers of clay, after which cross ribs are inserted. Other methods employ the extruding of the clay, but such methods have not produced a satisfactory article. Though terra cotta articles are not called upon to bear the heavy stresses borne by concrete building blocks, they are subjected to burning operations in their preparation, and in order to provide uniform treatment it is necessary that the cross sectional area of the parts of the terra cotta article be much thinner than in building blocks. It is a problem to prevent the terra cotta articles from warping in the burning operation and the cooling operation which follows.

An object of the present invention is to provide a terra cotta article having relatively great strength per unit of weight and so formed that the matter of burning is simplified over prior practice.

A further object is to provide a terra cotta article having sections which are much thinner than has been the practice heretofore, whereby improved uniformity of material is had.

A further object is to provide an improved terra cotta article which has improved support for the front face of said article, whereby the tendency of said front face to sink is minimized.

Further objects will appear as the description proceeds.

Referring to the drawings—

Figure 1 shows a terra cotta article looking at it from the rear side and showing holes extending from said rear side and longitudinal holes spaced between said first mentioned holes;

Figure 2 is a section taken along the plane indicated by the arrows 2—2 of Figure 1;

Figure 3 is a rear view of a slightly modified terra cotta article;

Figure 4 is a side view of a terra cotta article having an irregular front surface;

Figure 5 is a view illustrating a tool which may be used in forming an article such as shown in Figure 4;

Figure 6 is a sectional view illustrating a clay removing tool which may be used in the practice of the present invention;

Figure 7 is a sectional view taken along the plane indicated by the arrows 7—7 of Figure 6;

Figure 7a is a view in elevation of the tool shown in Figures 6 and 7, illustrating means for insuring the ready removal of said tool from the clay; and

Figure 8 is a modified form of clay removing tool.

Referring first to Figures 1 and 2, a terra cotta article is indicated by the numeral 10, which article is provided with holes 11—11, which holes extend from the rear wall 12 of said article to a region spaced from the front wall 13 of said article, whereby said front wall 13 is imperforate. Said article 10 is provided with the longitudinally extending holes 14, which holes 14—14 are disposed intermediate of rows of said holes 11—11.

Referring now to Figure 3, a terra cotta article is disclosed in which the holes 15—15 extending from the rear wall thereof are symmetrically disposed relative to one another. In a practical embodiment of the present invention said holes 15—15 are about two inches in diameter. In the spaces defined by sets of four of said relatively large holes 15—15 are smaller holes 16—16, which in said practical embodiment are about $\frac{3}{4}$ of an inch in diameter.

Referring to Figure 4, it will be noted that the terra cotta article having the irregular front face is provided with holes extending from the back wall thereof, which holes are of varying depths, depending upon the dimensions between said back wall and the various portions of said irregular front face. It will be noted that each of the holes hereinbefore referred to is of substantially uni-

form diameter from the bottom thereof to the back wall of the terra cotta article.

It is an important feature of the present invention that the holes in the terra cotta articles are provided by removing the clay; said clay being bored out, cut out, or punched out, to provide said holes. The terra cotta article may be formed in a mold 17, and clay of uniform texture may be filled into said mold, after which the holes referred to are provided by removing the clay. Holes extending from the rear of the terra cotta article may be provided by gangs of clay removing tools. Figure 5 illustrates in side elevation a gang of tools suitable for providing holes in the terra cotta article shown in Figure 4. The clay removing tools are indicated by the numerals 18-18, said tools being adjustably mounted within the head 19, which may be supported in any preferred manner.

Figures 6, 7 and 7a illustrate one form of tool which may be used, said tool comprising a cylinder 20 having a wire 21 diametrically disposed across the lower end thereof. It will be clear that the cylinder 20 may be inserted into the clay and then given a half turn. Said half turn will result in the cutting of a column of clay which will be removed with the cylinder 20. In order to prevent the cylinder 20 from becoming air locked within the clay, the exterior of said cylinder is provided with a plurality of uniformly spaced grooves 21A-21A, which permit access of air between said cylinder 20 and the clay. Said grooves 21A-21A are preferably slanting from top to near the bottom of the tool, or they may be arranged spirally. The grooves 21A-21A should stop a little short of the lower cutting edge of the cylinder in order that said lower cutting edge may be intact.

Figure 8 represents another form of clay removing tool comprising an auger 22 disposed within the cylinder 23.

By reason of the present invention, uniformity of material is insured, said uniformity not being disturbed after having been first determined, and perfect bonding is therefore provided. According to the present invention, greater strength is had, the material having arch construction, whereby strength and weight may be coordinated. The matter of burning is greatly simplified, inasmuch as the sections can be much thinner than has been the case heretofore. With this thinner material it is comparatively simple to get uniform treatment. Better and straighter ware is provided, for the reason that the perforations are small and numerous, giving more support to the surface of the material and avoiding the present tendency of terra cotta ware to sink between the ribs. The matter of drying is simplified by the present invention, due to the uniform thin structure. Inasmuch as no filling is required, strength is greatly increased. By reason of the pro-

vision of a large number of small dead air spaces, heat and sound insulation are improved over prior practice. The present invention has the further advantage that it provides an article which is easier to refire than has been the case heretofore, this advantage accruing from the fact that the invention involves relatively thin sections, which, it will be noted, are disposed transversely to one another. A further advantage accrues from the fact that the terra cotta article as illustrated in Figures 3 and 4 is closed on all sides but one, thereby giving a good hold for mortar and saving cost of backing material.

Many modifications will occur to those skilled in the art. It is intended to cover all such modifications that fall within the scope of the appended claims.

What is claimed is—

1. A terra cotta article having an imperforate front face, a plurality of symmetrically arranged round holes of uniform diameter each having its axis normal to said face and other symmetrically arranged round holes having their axes normal to said face, said other holes being of less diameter than said first-mentioned holes and disposed in the material defining sets of four of said first-mentioned holes.

2. A terra cotta article having an imperforate front face and a plurality of ribs normal to said front face in supporting relationship with one another, said ribs being disposed generally in transverse relationship with one another and being defined by round holes arranged as closely together as practicable, each of said holes being of uniform diameter from the bottom thereof to the rear face of said terra cotta article.

3. A clay article suitable for burning to produce a terra cotta article, said clay article having an imperforate front face, a plurality of symmetrically arranged round holes of uniform diameter, each having its axis normal to said face, and other symmetrically arranged round holes having their axes normal to said face, said other holes being of less diameter than said first-mentioned holes and disposed in the material defining sets of four of said first-mentioned holes.

4. A clay article suitable for burning to produce a terra cotta article, said clay article having an imperforate front face and a plurality of ribs normal to said front face in supporting relationship with one another, said ribs being disposed generally in transverse relationship with one another and being defined by round holes arranged as closely together as practicable.

5. A terra cotta article having an imperforate front face, a plurality of symmetrically arranged round holes of uniform diameter extending toward said front face,

5 said holes having their axes parallel with one another, and other symmetrically arranged round holes having their axes parallel with the axes of said first-mentioned holes, said other holes being of less diameter than said first mentioned holes and disposed symmetrically in the material defining sets of four of said first mentioned holes.

6. A clay article suitable for burning to 10 produce a terra cotta article, said clay article having an imperforate front face, a plurality of symmetrically arranged round holes of uniform diameter extending toward said front face, said holes having their axes 15 parallel with one another, and other symmetrically arranged round holes having their axes parallel with the axes of said first mentioned holes, said other holes being of less diameter than said first mentioned holes and disposed symmetrically in the material defining sets of four of said first mentioned holes.

Signed at Chicago, Illinois, this 7th day of November, 1928.
